(57) CLAIM

The ornamental design for a youth tongue hygiene device as shown and described.

DESCRIPTION

FIG. 1 is a perspective view of a first embodiment of a youth tongue hygiene device showing my new design;

FIG. 2 is a top view of the youth tongue hygiene device of
FIG. 1;

FIG. 3 is a bottom view of the youth tongue hygiene device
of FIG. 1;

FIG. 4 is a right side view of the youth tongue hygiene
device of FIG. 1;

FIG. 5 is a left side view of the youth tongue hygiene device
of FIG. 1;

FIG. 6 is a rear view of the youth tongue hygiene device of
FIG. 1;

FIG. 7 is a front view of the youth tongue hygiene device of
FIG. 1;

FIG. 8 is a cross-sectional side view of the youth tongue
hygiene device of FIG. 1, taken along line 8-8 in FIG. 2;

FIG. 9 is a perspective view of a second embodiment of a youth tongue hygiene device;

FIG. 10 is a top view of the youth tongue hygiene device of
FIG. 9;

FIG. 11 is a bottom view of the youth tongue hygiene device
of FIG. 9;

FIG. 12 is a right side view of the youth tongue hygiene
device of FIG. 9;

FIG. 13 is a left side view of the youth tongue hygiene
device of FIG. 9;

FIG. 14 is a rear view of the youth tongue hygiene device of
FIG. 9;

FIG. 15 is a front view of the youth tongue hygiene device of FIG. 9; and,

FIG. 16 is a cross-sectional side view of the youth tongue
hygiene device of FIG. 9, taken along line 16-16 in FIG. 10.
